SHOE ACCESSORY

Morris Resnik, Bronx, N. Y.

Application April 16, 1936, Serial No. 74,689

2 Claims. (Cl. 36—55)

This invention relates to shoes and accessories therefor.

An object of this invention is to provide a shoe having highly improved means incorporated into the shoe quarter for reinforcing or protecting the same and preventing buckling thereof, the construction being such that wear on the hose is minimized and the necessity for a shoe horn in donning the shoe is eliminated.

10 A further object of this invention is to provide a device of the character described which may replace the usual counter, and be incorporated into new shoes or applied to shoes now in use, for keeping the shoe in shape and preventing turning of the ankle, while preventing calluses.

Another object of this invention is to provide a durable shoe of the character described which shall be inexpensive to manufacture, attractive 20 in appearance, comfortable to wear, and withal, practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of this application will be indicated in the following claims.

30 In the accompanying drawing, in which is shown one of the various possible illustrative embodiments of this invention,

Fig. 1 is a side elevational view of a shoe embodying the invention with parts broken away to show the interior of the shoe,

Fig. 2 is a top plan view of the rear portion of the shoe shown in Fig. 1, with parts broken away to show the interior construction,

Fig. 3 is a partial cross-sectional view taken 40 on line 3—3 of Fig. 2,

Fig. 4 is a perspective view of the shoe accessory embodying the invention, before application to the shoe; and

Fig. 5 is a cross-sectional view taken on line 45 5—5 of Fig. 3.

Referring now in detail to the drawing, 10 designates a shoe provided with an accessory 11 embodying the invention. The shoe 10, here shown for the purpose of illustration only as a lady's shoe, may be of any usual construction and has a heel 12, an outer sole 13, a quarter portion 15 and an inner sole 16.

The accessory 11 may be made of metal, celluloid, papier-mâché, leather, composition or any 55 other suitable material. The same has a portion

18 of curved horizontal cross-section adapted to fit snugly against the inside surface of the shoe quarter.

Said portion 18 narrows toward the bottom and terminates in a forwardly projecting flat foot 5 portion 19 disposed beneath the inner sole 16. Said portion 19 has an opening 20 to receive a tack or nail 20 driven into the heel 12. The portion 18 of said member 11, increases in extent forwardly on both sides toward the top. Looking 10 down on said member, the top has a horseshoe shape as shown in Fig. 2.

The top portion of said member 11 is rolled outwardly over the top edge 15a of the quarter 15 as at 20a, forming a channel. The channel is 15

wider at the rear and narrows gradually toward the front where the edge of the shoe is gripped as shown in Fig. 3. Prongs 24 may be formed by piercing the inner surface of portion 18 adjacent the forward ends to help grip the leather 20 of the shoe. Furthermore the forward ends of rolled over portions 20a may be formed with downwardly extending prongs 25 which may be pressed inwardly as shown in Fig. 5, after the accessory is incorporated into the shoe. The 25 inner surface of member 11 is preferably very smooth or polished. Such construction will save the hose from tearing around the heel.

Furthermore, with my improved construction, there is no need to use a shoe horn in donning 30 the shoe. The shoe is also kept in shape and prevents the ankle of the wearer from turning. Calluses at the heels or ankles are also prevented.

The rolled or turned over portion 20a may be studded with ornaments, stones or jewels to enhance the appearance of the shoe.

It will be understood that shoes provided with my improved protector are comfortable to wear and have a longer life. The accessory may be incorporated into new shoes or applied to shoes 40 now in use, either men's or women's, to replace the usual stiffening counter.

It will thus be seen that there is provided a device in which the several objects of this invention are achieved, and which is well adapted 45 to meet the conditions of practical use.

As various possible embodiments might be made of the above invention, and as various changes might be made in the embodiments set forth, it is to be understood that all matter 50 herein set forth or shown in the accompanying drawing is to be interpreted as illustrative and not in a limiting sense.

Having thus set forth and disclosed the nature 55 of this invention, what is claimed is:

1. A shoe accessory comprising a portion of curved horizontal cross-section adapted to fit within the rear of a shoe, and having at the top an outwardly and downwardly rolled portion 5 and forming a channel gradually decreasing in width in transverse cross-section from the rear toward the front on both sides, the rolled over portion being adapted to provide a space between the shoe and said rolled over portion at the rear 10 and the forward ends of the rolled over portion being adapted to contact the shoe and being provided with prongs to be embedded in the shoe.

2. In combination with a shoe, a member com-

prising a portion contacting the inner surface of the rear portion of the shoe and being provided with a portion rolled over the top edge of the shoe and forming a channel, and having a forwardly extending foot portion disposed over the heel of the shoe and formed with an opening to receive a nail, the channel formed by the rolled over portion decreasing in width in transverse cross-section gradually from the rear toward the front on both sides, the forward ends of the 10 rolled over portion contacting the shoe and being formed with prongs embedded in the shoe.

MORRIS RESNIK.
